UNITED STATES PATENT OFFICE.

WILLIAM G. BETZ, OF BUFFALO, NEW YORK.

PNEUMATIC ACTION FOR PIANOS.

1,197,596.

Specification of Letters Patent. Patented Sept. 12, 1916.

Application filed May 8, 1914. Serial No. 837,130.

To all whom it may concern:

Be it known that I, WILLIAM G. BETZ, a citizen of the United States of America, residing in Buffalo, county of Erie, and State 5 of New York, have invented certain new and useful Improvements in Pneumatic Actions for Pianos, of which the following is a specification.

My invention relates to pneumatic actions 10 for pianos, the principal features looking more particularly to a simplified valve construction and the method of supporting the action levers controlled thereby. Referring more particularly to the valve mechanism, I 15 have found that with my construction a very effective control of the hammer action is secured and one in which a smaller air duct or vent in the tracker bar may be used and still secure a very good operation. Also I 20 have so hung the action levers that said levers and their supporting arms may be independently removed.

I will now refer to the accompanying drawing for a better understanding of my 25 invention in which like reference characters indicate like parts and in which—

Figure 1 is a sectional view illustrating the control mechanism of one key; Fig. 2 is a face view of one valve mechanism with 30 the cover of the air chamber removed; Fig. 3 is a side elevation of a valve lever; Fig. 4 is a left side view of Fig. 3; Fig. 5 is a detail view of a combined valve lever support and valve seat; and Fig. 6 is a sectional view through the center of Fig. 5.

In the preferred embodiment of my invention as illustrated, I provide a so-called air chest or chamber A, comprising vertically disposed facing walls 1 and 2 having 40 spacers as 3, 4, the cap or wall 2 being attached by screws 5 so that it may be readily removed. This chamber A is, of course, of such a length and width as to suitably take care of the desired number of valve mechanisms, as will be readily understood.

A single valve mechanism B is shown comprising a plate 6 having a centrally disposed air port 7 formed so as to provide a valve seat 8, and above said port a pair of 50 inwardly projecting ears 9 are formed, having concave formations 10 for supporting the valve lever shaft. Plate 6 is secured to the inner surface of the wall 1 preferably by screws 11, the valve seat 8 projecting into a chamber 12 having a valve seat

13, said chamber 12 having an atmosphere duct 14 and bellows duct 15.

A valve lever 27 is provided, having a pointed shaft 28, which is sprung between the resilient arms 9 and held between the 60 concaved portions 10 in such a manner that the depending lever 27 is free to reciprocate without any lateral movement, thus doing away with guides, such as have been previously used. At the free end of lever 27, 65 a valve 29 is adjustably attached by means of a screw 30, said valve having facings preferably of leather, which act upon valve seats 8 and 13.

At a point preferably intermediate of 70 the pivoted end of lever 27 and the valve support 30, a buffer 31 is adjustably secured, said buffer co-operating with a diaphragm 32, which is preferably of rubber or leather, and suitably fastened over the 75 diaphragm actuating chamber 33. Chamber 33 is preferably round, and a duct 34 leads therefrom to a tube 35 extending to its tracker bar port 36. A connecting duct 37 leads from the main air chamber A to each 80 duct 34, there being a cap 38 provided with a small opening inserted in each duct 37 to allow only a small flow of air. A tube from chamber A is also connected to the 85 vacuum pump to create a vacuum in chamber A in a well known manner.

It will, of course, be understood that in 90 using my invention, the air chest is made wider than shown, and the associated bellows and valve mechanisms are staggered in accordance with well known practice.

An action-operating bellows C is suitably fastened to the wall 1 in connection with duct 15 and is connected to a hammer action lever 16 by means of a connecting 95 rod 17, which is pivotally attached at its upper end and held to the bellows extension 18 by a pair of ball faced nuts 19. Each action lever 16 is pivotally secured to an arm 20, which is detachably secured to a 100 rack or bar 21 by means of screws 22, said rack being suitably supported, preferably by screws 23. An overhanging portion 26 of arm 20 carries an adjustable stop 24, whereby the upward travel of action lever 16 is determined. An adjustable buffer screw 26 is also carried by lever 16 which acts upon the action mechanism D, as will 105 be readily understood.

In the operation of the action, a vacuum 110

is created in the air chamber A by suitable means, and with the music sheet covering the duct 36 a vacuum is also created in duct 34. Thus the atmospheric pressure against valve 29 tends to hold valve lever 27 in its normal or inoperative position, and therefore the bellows C is maintained open. Upon opening tracker port 36, duct 34 tends to come up to atmospheric pressure, resulting in a pressure against diaphragm 32 by the pressure in chamber 33. Buffer 31 therefore acts upon lever 27, which causes valve 29 to normal or air chamber port seat and engage the atmosphere duct seat 13, whereby the bellows chamber is connected to the chamber A by ducts 15. A vacuum is thus created in the bellows chamber, allowing the atmospheric pressure to close the bellows, whereby the arm 18 rises and through connecting rod 17 and lever 16 the hammer action mechanism D is actuated. Upon closure of port 36 again, duct 35 and chamber 33 being connected to chamber A again have the pressure therein reduced so that the atmospheric pressure acting upon valve 29 through duct 14, forces the valve 29 against its seat 8 and thus the bellows chamber being connected to atmosphere through ducts 15, 14, again opens and stores the action mechanism D.

What I claim as new and desire to secure by Letters Patent is:

1. A pneumatic action for pianos comprising an air chamber, a valve plate secured to an inner vertical wall thereof, and having an air port and valve seat, a pair of inwardly projecting resilient arms for said plate disposed above the port and having facing concave portions, a valve lever having a pointed-end shaft supported by said concave portions whereby said lever depends opposite said port, and a valve for said port supported by said lever.

2. A pneumatic action for pianos comprising an air chamber, a valve plate secured to an inner wall thereof, a pair of inwardly projecting arms for said plate having facing concave portions, a valve lever having a pointed supporting shaft carried by said concave portions, said valve plate having an air duct and a valve seat on the outer side thereof, and a valve for said seat having a valve stem projecting through said port and carried by said lever.

ing an air chamber, a valve plate secured to an inner wall thereof, a pair of inwardly projecting arms for said plate having facing concave portions, a valve lever having a pointed supporting shaft carried by said concave portions, said valve plate having an air duct and a valve seat on the outer side thereof, and a valve for said seat having a valve stem projecting through said port and carried by said lever.

3. A pneumatic action for pianos comprising an air chamber having facing inner walls, a valve lever disposed within said chamber and pivotally supported at one end in said chamber, an air port through one of said walls opposite the free end of the lever, a valve carried at the free end of the lever for controlling said port, a plate secured to one of said walls for supporting said lever and having a seat for said valve, an action operating bellows connected with said port, a diaphragm on the opposite wall, an air duct whereby said diaphragm may be oscillated, and a buffer carried by said lever in operative relation with said diaphragm.

4. A pneumatic action for musical instruments comprising an air chamber, a valve plate secured thereto, a valve lever, a pointed shaft for said lever, a coöperating valve and port for said lever and plate respectively, and a pair of resilient arms extending from said plate having facing concave portions for supporting said valve lever by said pointed shaft and whereby said arms may be readily sprung apart to remove said lever.

Signed by me at Chicago, county of Cook, and State of Illinois, in the presence of two witnesses.

WILLIAM G. BETZ.
